Patented Sept. 22, 1914.

UNITED STATES PATENT OFFICE.

FRANK LEE RICHARDS AND ANDERSON HARRISON SHULL, OF FARMINGTON,
MINNESOTA.

WINDOW.

1,111,323.

Specification of Letters Patent. Patented Sept. 22, 1914.

Application filed December 4, 1913. Serial No. 804,607.

To all whom it may concern:

Be it known that we, FRANK L. RICHARDS and ANDERSON H. SHULL, citizens of the United States, and residents of Farmington, 5 in the county of Dakota and State of Minnesota, have invented a new and Improved Window, of which the following is a full, clear, and exact description.

Our invention relates to a window frame 10 adapted to receive either a storm sash or the sashes or frames of screens the screens and storm sash being interchangeable. By means of our invention, the ordinary window frame when originally constructed, 15 may be modified at the outer portion to receive the storm sashes or screens, or in the case of window frames already in position, or made up conventionally, may be provided with an auxiliary frame to receive the interchangeable storm sashes and screens.

The invention provides for the insertion and removal of the storm sashes and screens, or the changing of the same, from the interior of a room simply by raising the usual 25 lower sash of a sliding window, to give access to the frames.

The invention will be particularly explained in the specific description following.

Reference is to be had to the accompanying drawings forming a part of this specification, in which similar characters of reference indicate corresponding parts in all the views.

Figure 1 is a front view of a window embodying our invention; Fig. 2 is a vertical section through the window frame and through the stiles of the sashes; Fig. 3 is a fragmentary vertical section showing the upper sash in position, and with the lower 35 sash in the act of being placed or removed; Fig. 4 is a perspective view of a fragment of a window frame; Fig. 5 is a horizontal section on the line 5-5 in Fig. 1; Fig. 6 is a view similar to Fig. 5, but illustrating the 40 screens in place of the storm sashes; Fig. 7 is a fragmentary front view of the upper storm sash; Fig. 8 is a fragmentary view of the lower storm sash; and Fig. 9 is a fragmentary detail showing upper and lower 45 screens in the window frame.

In carrying out our invention a window frame 10 is provided in the stiles thereof, at the upper portions of the latter and in the top rail, with a groove 11, thereby providing 50 an inner bead or stop 12. The stops are

cut away from about the line of the meeting rails of the sashes, thereby providing rabbets 13 below the line of the meeting rails, said rabbets being complementary to the grooves 11.

In connection with the window frame thus formed, an upper storm sash 14 may be employed and a lower storm sash 15. The upper sash 14 is provided with a bead or flange 14^a at the sides and top to fit the 60 groove 11, and the bottom rail of the upper sash is rabbeted at the outside, as at 14^b; while the top rail of the lower sash 15 is reversely rabbeted at the front, as at 15^b. The upper sash is thus provided with a depending bead or flange 14^c on the lower rail which is received in the rabbet 15^b of the lower sash. The stiles of the lower sash 15 are rabbeted, as at 15^a, to conform to the rabbets 13.

With the described construction the upper sash 14 is first placed in position by being passed into the lower portion of the frame 10, the side flanges 14^a being accommodated in the rabbets 13 of said frame. 80 The sash is then raised to its position in the top of the frame, the flange or bead 14^a sliding in the grooves 11. The lower sash 15 is now set in the frame beneath the upper sash, the meeting rails of the upper and lower sashes being caused to overlap by reason of the rabbets 14^b, 15^b. With the lower sash in position, the upper sash rests thereon and the overlapped meeting rails form a tight joint for the sashes. Turn-buttons 16 or equivalent means on the frame 85 serve to retain the lower sash against outward movement.

In warm weather provision is made for substituting for the storm sashes 14, or 15, upper and lower screen sashes or frames 20, 21, as in Figs. 5 and 6. The upper screen has beads 22 formed on the stiles thereof to fit the grooves 11, said beads corresponding with the beads 14^a on the storm sash 14. 95 The lower sash screen or frame is provided at the outer upper corners of the top rail with recesses 21^a to conform to the lower ends of the stops 12, and the side rails of the lower sash are rabbeted at the outer side, as at 20^a, similarly to the rabbets 15^a on the lower storm sash 15, and thus said side rails conform to the rabbets 13 in the window frame 10.

Having thus described our invention, we 110

claim as new and desire to secure by Letters Patent:

1. In a window, a window frame having vertical grooves in the stiles thereof at the upper portions, and rabbets in said stiles below and complementary to the said grooves, the said frame presenting inner beads at the front of the grooves, said beads terminating at approximately the horizontal center of the frame and overhanging the rabbets, an upper auxiliary frame having beads on the stiles thereof slidably fitting the said grooves, and a lower auxiliary frame removably fitting in the rabbeted lower portion of the window frame beneath the upper sash, the meeting rails of the auxiliary frames being in vertical alinement and reversely rabbeted.
2. In a window, a window frame having the stiles thereof formed with vertical grooves in the upper half and rabbeted at the lower half in line with the grooves, upper and lower auxiliary frames removably fitting the window frame and in vertical alinement with each other, the lower auxiliary frame having its stiles rabbeted reversely to the rabbets of the window frame, and the upper sash being supported on the top of the lower sash and provided on the stiles thereof with beads slidably fitting the grooves of the window frame.
3. In a window, a window frame having the stiles thereof formed with vertical grooves in the upper half and rabbeted at the lower half in line with the grooves, up-

per and lower auxiliary frames removably fitting the window frame and in vertical alinement with each other, the lower auxiliary frame having its stiles rabbeted reversely to the rabbets of the window frame, and the upper sash being provided on the stiles thereof with beads slidably fitting the grooves of the window frame.

4. In a window, a window frame having vertical grooves in the upper half of the stiles thereof presenting inner vertical beads terminating at the approximately horizontal center of the frame, and rabbeted at the lower half in vertical alinement with the vertical grooves, the beads overhanging the upper ends of the rabbets, an upper auxiliary frame having vertical beads on the stiles thereof slidably fitting the grooves of the window frame, and the lower auxiliary frame received in the rabbeted lower portion of the window frame and supporting the upper auxiliary frame, the said lower frame having its stiles rabbeted reversely to the rabbets of the window frame and having its upper, outer corners recessed to accommodate the lower terminals of the beads.

In testimony whereof we have signed our names to this specification in the presence of two subscribing witnesses.

FRANK LEE RICHARDS.
ANDERSON HARRISON SHULL.
